UNITED STATES PATENT OFFICE.

MIKE LUBAS, OF NAUGATUCK, CONNECTICUT.

INK-WELL.

1,162,791.

Specification of Letters Patent.

Patented Dec. 7, 1915.

Application filed August 16, 1915. Serial No. 45,757.

To all whom it may concern:

Be it known that I, MIKE LUBAS, subject of the Emperor of Austria-Hungary, residing at Naugatuck, in the county of New Haven and State of Connecticut, have invented certain new and useful Improvements in Ink-Well, of which the following is a specification.

This invention relates to certain new and useful improvements in ink-wells.

The primary object of this invention is the provision of an inkwell that is easy and inexpensive to manufacture and which is especially serviceable for desk use, the same being provided with a closing means for preventing evaporation of the ink.

A further object of the invention is the provision of an inkwell which is readily opened for use, but closable in an air-tight condition when not in use, thereby preventing an evaporation of the contained ink and thus conserving the same.

A still further object is the provision of a closable inkwell so arranged that the prevention of loss of the ink is effected either by evaporation or spilling when the same is closed.

With these general objects in view and others that will appear as the nature of the invention is better understood, the same consists in the novel combination and arrangement of parts hereinlater more fully described, illustrated in the accompanying drawings, and pointed out in the appended claims.

In the drawings forming a part of this application and in which like designating characters refer to corresponding parts throughout the several views, Figure 1 is a central transverse sectional view through the device in its open position. Fig. 2 is a similar view thereof in its closed position partially broken away. Fig. 3 is a top plan view of the device in its closed position. Fig. 4 is a transverse sectional view taken upon line IV-IV of Fig. 1, and Fig. 5 is a perspective view of the closure member detached.

Referring more in detail to the drawings, an ink-well 10 is provided preferably formed of some vitreous material and the same may be of any desired shape, but is herein illustrated substantially cubical in form and provided with an inner ink chamber 11.

A pen receiving opening 12 is arranged

substantially centrally of the top 13 of the ink-well, while a closure slide 14 is positioned in the ink-well slidably mounted within opposite transverse slots 15 of a slide 60 receiving recess 16 formed upon the inner side 17 of the said top 13, the said recess traversing the said top opening 12.

A slot or opening 18 is arranged at the forward side of the ink-well and the slide 65 14 is positioned therethrough having its forward end provided with a projecting handle 19 by means of which the slide 14 is opened and closed at will. A pen guard 20 consisting of a tapered tube has one end 70 screw-threaded within an opening 21 of the slide 14, the said slide opening being of less diameter than the top opening 12 of the ink-well. Packings 22 are carried by the lower side of the slide 14 extending in parallelism 75 at points opposite the pen guard 20 and whereby the slide is mounted in an air tight manner slidable within the ink-well.

It will thus be seen, that the pen guard 20 may be positioned directly beneath the top 80 pen-receiving opening 12 of the ink-well and in which position the ink in the chamber 11 is readily accessible to a pen through the top opening 12 and interiorly of the pen guard 20 within which the ink may rise to 85 the same level as the ink in the chamber 11. When the ink-well is not in use, the ink-well opening 12 may be readily closed by grasping the slide handle 19 and withdrawing the slide 14 to the position illustrated in 90 Fig. 2 of the drawings, and so as to underlie the said opening 12, it being understood that the packings 22 insure a tight-engagement between the slide 14 and the upper face 23 of the receiving recess 16, the slide 95 also having a fluid-tight sliding engagement within the slot 18. It will be noted that the tapered guard 20 is inserted within the opening 21 of the slide 14 by being positioned through the top opening 12 of the 100 ink-well and then screwed into the said slide opening, spanner wrench receiving sockets 24 being provided in the outer end of the said guard 20. It will thus be evident that an ink-well is provided which is inexpensive 105 to manufacture, but which at the same time actively carries out the objects heretofore enumerated.

While the form of the invention herein shown and described is what is believed to 110 be the preferred embodiments thereof, it is nevertheless to be understood that minor

changes may be made without departing from the spirit and scope of the invention as set forth in the claims.

What I claim as new is:—

- 5 1. In a device of the class described comprising a vitreous body having an ink-receiving chamber therein and further having a pen entrance opening in the top thereof and a slot in its forward side, a slide shiftably positioned through the said slot and having a path of movement transversely of said opening, the said slide being provided with an opening therein intermediate the ends thereof, and a tubular tapered pen
- 10 guard secured through the said slide opening and projecting inwardly of the said chamber.
- 15 2. A device of the class described comprising an ink-well member having a pen-receiving opening in the top thereof, and a transverse recess in the inner face of the

said top and traversing the said opening, the said well member having a slot in its forward side communicating with the said recess, a slide shiftably mounted through 25 the said slot and within the said recess, partially longitudinally extending fluid-tight packings carried by the underside of the said slide, the said slide being provided with a substantially central screw-threaded 30 opening therethrough, a tapered tubular pen guide positioned through the said top opening and having threaded engagement with-in the said slide opening and positioned inwardly of the well, the said guard being 35 provided with wrench-hold sockets in its outer end and a projecting operating handle carried by the said slide outwardly of the said slot.

In testimony whereof I affix my signature. 40

MIKE LUBAS.
